Des. 99,568

UNITED STATES PATENT OFFICE

99,568

DESIGN FOR A CRYSTAL OR SIMILAR ARTICLE

Philip Cohn, New York, N. Y.

Application March 7, 1936, Serial No. 61,518

Term of patent 14 years

To all whom it may concern:

Be it known that Philip Cohn, citizen of the United States and resident of New York, in the county of New York and State of New York, has invented a new, original, and ornamental Design for a Crystal or Similar Article of which the following is a specification, reference being had to the accompanying drawing forming part thereof, in which,

Fig. 1 is a front elevational view of a crystal embodying my new design; and

Fig. 2 is a side elevational view thereof.

I claim:

The ornamental design for a crystal or similar article, substantially as shown.

Dated, New York city, March 2nd, 1936.

PHILIP COHN.
